UNITED STATES PATENT OFFICE.

JOHN VANDER BEUGLE, OF NEW YORK, N. Y., ASSIGNOR OF TWO-
THIRDS TO JOSEPH MANHEIMER AND CHARLES A. WIMPFHEIMER,
OF NEW YORK, N. Y.

NON-REFILLABLE BOTTLE.

SPECIFICATION forming part of Letters Patent No. 711,692, dated October 21, 1902.

Application filed April 23, 1901. Serial No. 57,139. (No model.)

To all whom it may concern:

Be it known that I, JOHN VANDER BEUGLE, a citizen of the United States, and a resident of the borough of Manhattan, in the city, county, and State of New York, have invented 5 a new and Improved Non-Refillable Bottle, of which the following is a full, clear, and exact description.

The purpose of the invention is to provide 10 a simple inexpensive device and means for securing it in the neck of a bottle which will permit the contents of a bottle to be freely and readily emptied, but which will effectually prevent the bottle from being refilled, 15 so that the bottle cannot be offered a second time as an original package.

The invention consists in the novel construction and combination of the several parts, as will be hereinafter fully set forth, 20 and pointed out in the claims.

Reference is to be had to the accompanying drawings, forming a part of this specification, in which similar characters of reference indicate corresponding parts in all the figures.

25 Figure 1 is a vertical section, considerably enlarged, of my device in place in a bottle-neck. Fig. 2 is a face view of the outer end plate or end piece of the rotating cylinder. Fig. 3 is a face view of the fixed disk immediately below the cylinder. Fig. 4 is a face view of the fixed disk below the valve-disk. Fig. 5 is a face view of the sliding valve-disk. Fig. 6 is a side view of the operating parts of my device removed from their inclosing shell. 30 Figs. 7 and 8 are modifications of the means for holding the device in position in the bottle-neck.

A represents the neck of a bottle, in which an ordinary cork B may be used. The neck 40 of the bottle is usually provided with diametrically opposite openings 10, which openings receive pins 11, and these pins extend into a ring or band 12, which fits snugly to the inner face of the neck of the bottle at a point 45 below the cork, and this ring or band 12 is adapted to prevent the device to be hereinafter described from being drawn out from the bottle. The pins 11 are preferably concealed by an exterior collar 13, screwed or otherwise

attached to the neck of the bottle over the 50 openings 10 and pins 11.

The device proper consists of a cylindrical shell 14, which shell may be held in the neck of the bottle by frictional contact or by positive means, as described later, and the upper 55 end of the shell is preferably made to engage with the under face of the retaining ring or band 12. A disk 15 is horizontally secured in the shell 14 at or near the bottom of the shell, the shell itself being open at both top and 60 bottom. This disk is held in place by frictional contact of its periphery with the inner face of the shell or by suitable securing means. The disk 15 is provided with a central upwardly-extending stud or post 16, lying substantially in the axis of the bottle-neck, circular in cross-section where it passes through the disk 15, but becoming polygonal in cross-section immediately outside the disk. Its lower end is riveted down on the disk or secured in 70 any other suitable way. (See Fig. 1.) In the disk 15 are provided openings 17, one at each side of the post or stud, the openings being diametrically opposite and of circular form. In connection with this fixed disk 15 an upper or 75 valve disk 18 is employed. This valve-disk is of slightly less diameter than the disk 15 and is free to slide in the shell 14 and is guided in its movement by the post or stud 16, which passes through a central polygonal 80 opening 19 in the valve-disk, as shown in Fig. 1. The valve-disk is perforated with two diametrically opposite openings 20, also usually of circular form, but when the valve-disk is in position in the shell the openings 20 are 85 out of registry with the openings 17 in the fixed disk 15. The disk 15 serves as the seat of the valve-disk 18. When the valve-disk 18 is in its lower position, as shown in Fig. 1, it lies against and over the openings in the fixed 90 disk 15 and effectually closes the same. To this end the valve-disk should be sufficiently heavy to adjust itself on the fixed disk 15 to close the openings 17 in the latter whenever the bottle is placed in an upright position or 95 in an inclined position slightly above the horizontal.

Throughout the extent of the travel of the

valve-disk 18 the stud 16 is polygonal in cross-section. Beyond this point it once more becomes circular in cross-section and continues so to its upper end. Secured at the lower part 5 of this circular portion of the stud 16 is the fixed disk 25, being provided with a suitable number of openings 26 through its face, such that when the valve-disk 18 lies against the disk 25 one or more of the openings 26 will always 10 register with the openings 20 of the valve-disk. The fixed disk 25 is of substantially the same diameter as the disk 15 and contacts frictionally with or is secured to the inclosing shell 14. Axially pivoted on the 15 circular portion of the stud 16 just beyond the fixed disk 25 is a hollow cylinder 27 of peculiar construction serving as a support for the flap-valve, to be later described. The cylinder 27 is of slightly less diameter than the disk 25, so that it is enabled to rotate freely within the shell 14. It is composed of two end pieces 28 29, spaced apart and each provided through a portion of its face with a 20 convenient number of openings 31 32, preferably four. Over the periphery of the end pieces is drawn the cylindrical shell 30, forming the outer periphery of the cylinder. The end pieces are so adjusted that their openings shall be in line with each other, thus 25 forming, in effect, openings extending through the cylinder parallel with its axis. Within the cylinder on the side opposite the region containing the openings is placed a suitable weight 33, so as to bring the center of gravity 30 of the cylinder outside of or eccentric to the axial point of support. As the cylinder can rotate freely, it thus occurs that whenever the stud 16 is placed horizontally—as, for instance, when a bottle is placed on its side—the weight 35 within the cylinder causes the same to rotate, thereby assuming a position in which the openings are at the upper portion of the cylinder or above the axis. By reason of the number of openings 26 in the disk 25 the cylinder-openings 40 always register with some of the openings 26. Hinged to the outer face or end piece 28 of the rotating cylinder and coacting with the openings therein is a swinging door or flap-valve 34, the point of attachment 45 being opposite the weight in the cylinder, so that the door will swing down against the end piece 28 whenever the cylinder assumes a position with its weight 33 below its axis. The door may be aided in so closing by a weight 50 36, applied near its edge opposite its hinge, in case its own weight is not sufficient to cause it to close. The rotating cylinder is secured on the cylindrical portion of the stud 16 by a nut outside the face 28, and the door 34 is 55 provided with a raised portion or recess 35 to receive the nut, and thus permit the door to close tightly on the openings 31. Within the shell 14, but sufficiently beyond the door 34 to permit the same to open as far as desired, 60 is the perforated disk 23, secured in any desired manner, as by a bead 37, spun over the edge of the disk. This partition prevents the

introduction of a wire for the purpose of raising or holding raised the door 34. It is usually arched upward, as shown in Fig. 1. 70

Thus it will be observed that when the bottle is inclined the valve-disk will unseat itself and liquid will pass through the openings 17 in the fixed disk 15, through the openings 20 of the valve-disk and openings 26 of the fixed disk 25, and into the hollow cylinder. Passing through this the liquid will press on the outwardly-swinging door 34 and open the same in case the bottle has not been inclined beyond the horizontal. Of course when the bottle is inclined beyond a horizontal the door 34 opens of itself. Passing beyond the door 34, the liquid flows through the perforated partition 23 to the mouth of the bottle and is discharged therefrom. As soon as the bottle is returned to a horizontal position the door 34 will close. If an attempt is made to force liquid into the bottle, as by submerging the bottle on its side in the liquid, the door 34 will close and prevent the passage of liquid, and if pressure is exerted the valve 18 will also seat itself. 85

Fig. 7 shows a modification of the means for holding the shell 14 in position in the bottle-neck. The ring 12 is dispensed with. The shell 14 is provided with holes registering with the pins 11 and is located as to its upper portion in the space formerly occupied by the ring 12, so that the pins pass directly into the openings of the shell 14 and secure it in place. 90 As with the means of Fig. 1, the pins in turn are retained in position by the superposed screw-threaded ring 13. 95

Fig. 8 shows another modification of the means for holding the shell 14 in position in the bottle-neck. In this case the bottle-neck is blown with an outwardly-extending bead just above the point of location of the upper edge of the shell 14. After insertion of the device into the bottle-neck a split spring-ring 12' is inserted into the bottle-neck and snapped into the bead, the ring 12' being of sufficient thickness to project inwardly over the upper edge of the shell 14, which is thus secured against displacement or withdrawal. 110 115

I do not limit myself in the device above described to the specific relative location of the flap-valve and sliding valve, as I may place the flap-valve below the sliding valve.

Having described my invention, what I claim as new, and desire to secure by Letters Patent, is—

1. In a non-refillable bottle, a rotatable support axially pivoted within the bottle-neck, a flap-valve hinged to the said support, said support being weighted opposite the point of attachment of the flap-valve, whereby in horizontal position of the bottle the flap-valve is caused to assume a position with its hinge uppermost, substantially as described. 125

2. In a non-refillable bottle, a rotatable cylinder axially pivoted within the bottle-neck, openings through the said cylinder parallel with its axis, a flap-valve hinged to the said

cylinder and coacting with the said openings, and a weight carried by said cylinder opposite the point of attachment of the flap-valve, substantially as described.

5 3. In a non-refillable bottle, a rotatable cylinder axially pivoted within the bottle-neck, openings through the said cylinder parallel with its axis, a flap-valve hinged to the said cylinder and coacting with the said openings,

10 a weight carried by said cylinder opposite the point of attachment of the flap-valve, a valve-disk sliding axially within the bottle-neck, and a seat for said valve-disk, substantially as described.

4. In a non-refillable bottle, a rotatable support axially pivoted within the bottle-neck and eccentrically weighted, a flap-valve hinged to the said support, and a perforated disk located beyond the path of movement of the flap-valve, substantially as described. 15 20

In testimony whereof I have signed my name, in the presence of two subscribing witnesses, this 19th day of April, 1901.

JOHN VANDER BEUGLE.
